ONION PARING KNIFE

Charles H. Harvey, Jacksonville, Fla.

Application June 21, 1949, Serial No. 3,439

Term of patent 7 years

(Cl. D22—3)

To all whom it may concern:

Be it known that I, Charles H. Harvey, a citizen of the United States of America, residing at Jacksonville, in the county of Duval and State of Florida, have invented a new, original, and ornamental Design for an Onion Paring Knife, of which the following is a specification, reference being had to the accompanying drawing, forming a part thereof.

In the drawing—

Figure 1 is a bottom plan view of an onion paring knife showing my new design,

Figure 2 is a top plan view of the same,

Figure 3 is a side elevational view of the same with the shield in partly elevated position,

Figure 4 is a sectional view taken on the line 4—4 of Figure 2,

Figure 5 is a sectional view taken on the line 5—5 of Figure 4.

I claim:

The ornamental design for an onion paring knife, as shown.

CHARLES H. HARVEY.
